SOUND APPARATUS

Leo J. Buckley, Binghamton, N. Y.

Application August 27, 1934, Serial No. 741,581

5 Claims. (Cl. 181—31)

My invention relates to sound apparatus and has for its primary object the provision of a sound box in which a loud speaker such as is commonly used in radio receiving sets and the like, is mounted and which is so designed as to produce the audible translation of the sound waves emanating from the loud speaker diaphragm over a maximum frequency range and in natural character and tone.

10 It is known that when a loud speaker unit including the diaphragm which translates the electrical impulses into audible sound waves, is mounted within a box or container, the faithful translation of the sound waves of various frequencies and particularly those of the low frequency type is effected by the character of the box and the chamber therein within which the loud speaker is mounted. This is due to the fact that the diaphragm, usually of substantially cone 15 shape, during vibration, sets up the sound waves on both sides of the diaphragm. There is, of course, customarily provided an opening in the front wall or panel of the box directly behind which the loud speaker diaphragm is mounted so 20 that the sound waves emanating from the interior surface of the diaphragm pass directly to the atmosphere outside of the box. Ordinarily, however, the chamber in the box within which the loud speaker is mounted has been more or less 25 closed to the atmosphere except for such opening, with the result that the vibrations or sound waves emanating from the outside surface of the diaphragm meet with an air pressure comprising the air bottled up in the chamber and surrounding 30 the diaphragm.

35 I have discovered that while a certain amount of this air pressure or air resistance within the chamber to the sound waves is essential for the audible translation of certain of the sound waves, 40 particularly those of the low frequency, I have also discovered that the amount of such air pressure depends upon several factors among which are the size of the chamber, the energy of the loud speaker unit, and the amount of free air 45 communication between the rear surface of the diaphragm and the atmosphere.

50 I am aware that others have recognized these conditions in part and have attempted to provide the required balance between the air pressure within the chamber and the atmosphere by providing channels of communication therebetween. In such attempts, however various other elements and means have been introduced which tend to render more difficult the delicate balance required 55 between the chamber and the atmosphere.

By my invention I have provided a very simple and economic structure by which the balance between the air within the chamber and the atmosphere can be easily obtained and regulated without the addition of extraneous elements such as hoods, tubes, interior casings, etc., and which by virtue of its simplicity and direct control makes possible a true translation of the vibrations of the diaphragm into audible sound waves.

5 One of the principal objects of my invention lies in the provision of an opening in the front board or panel of the box which is of such size with respect to the diameter of the diaphragm of the loud speaker and the air capacity of the box itself that for a loud speaker of given energy the proper 10 balance is obtained between the interior of the box and the atmosphere thus providing for a true 15 rendition of the original sound as translated by the loud speaker unit.

Another object of my invention is to provide 20 a means cooperating with the diaphragm in the chamber for affecting the amplitude of sound vibrations of certain frequencies without disturbing or affecting the other sound frequency waves emanating from the diaphragm.

25 Other objects and advantages in details of construction will be apparent as the description proceeds, reference now being had to the figures of the accompanying drawings forming a part of this application and wherein like reference numerals 30 indicate like parts.

In the drawings:

Figure 1 is a front view of a sound box embodying my invention.

Figure 2 is a sectional view thereof taken on 35 the line 2—2 of Figure 1.

Figure 3 is a detail sectional view taken on the line 3—3 of Figure 2.

Figure 4 is a front view of a slightly modified form of sound box embodying my invention.

Figure 5 is a sectional view taken on the line 5—5 of Figure 4.

Figure 6 is a front view of a still further modified form of sound box embodying my invention.

Figure 7 is a sectional view taken on the line 45 7—7 of Figure 6.

Figure 8 is a perspective view of the attachment used in connection with my invention.

Figure 9 is a front view of a further modified form of sound box embodying my invention.

Figure 10 is a sectional view thereof taken on 50 the line 10—10 of Figure 9.

This application is a continuation in part of my application Serial No. 671,670 filed May 18, 1933.

The reference character 1 refers generally to a sound box, the front wall 2 of which is provided with an opening 3 hereinafter referred to in more detail. Within the chamber 4, closed to the atmosphere except for the opening 3, there is suitably mounted as by means of a bracket 5 a loud speaker unit 6 of any desire type or construction.

This loud speaker unit is provided with the diaphragm 7 of the usual substantially cone shape which projects forwardly to a point in registry with the opening 3 in the front board or panel 2.

Adjacent the rear side of the box there may be provided guides 8 by means of which removable partition boards 9 and 10 may be inserted across

the rear of the box whereby to selectively change and reduce the volume of the box between the front board and the back, that is, reduce the size of the air chamber within which the loud speaker is mounted. This may be desirable with certain sizes and types of loud speakers and provides a means of "rough" adjustment to bring the volume of the sound chamber to the desired amount.

The diaphragm 7 is usually provided with a fastening rim 11 adjacent its front end and as a means of support this ring is connected at spaced points by means of the ears or lugs 12 to the front board 2 of the box. The size of these lugs 12 is such as not to interfere materially with the communication between the chamber 4 and the atmosphere.

The size of the opening 3 is extremely important depending, as before stated, upon the energy of the speaker and more particularly upon the volume of the chamber within which the speaker is mounted. It is also important that there be no intermediate elements between the rear surface of the diaphragm 7 and the opening 3. This is clearly illustrated in Figure 2 where it will be observed that free and direct communication exists between the chamber 4 immediately surrounding the diaphragm and the atmosphere, through the opening 3. If desired the front board 2 may be readily removable and replaceable with other front boards of the same size but provided with openings 3 of different sizes whereby the proper channel of communication between chamber and atmosphere may readily be provided.

As a practical example, the following construction has been found to give excellent results:

A substantially square sound box is provided, 16 inches deep by 21 $\frac{1}{4}$ inches square, made of beaver board or other suitable material, providing a surface of 16 square feet and containing a loud speaker of ordinary commercial design. The sound box is provided in its front board with an opening 14 inches in diameter, leaving a 1 inch passage around the outer edge of the diaphragm and its frame, allowing a direct passage between the chamber directly adjacent the outer surface of the diaphragm and the atmosphere. When the baffle attachment, hereinafter described, is used, a very faithful reproduction is obtained having a measured frequency response of from 35 cycles per second to 16,500 cycles per second.

In the operation of the invention the vibration of the diaphragm 7 and particularly the vibrations of the outer surface thereof, set up corresponding air waves within the chamber 4 and with the proper balance between the air in the chamber and the atmosphere through the opening 3, the widest possible range of frequencies will be rendered audible because of the proper influence of the air pressure within the chamber upon the emanating sound waves. Thus by providing the proper sized opening 3 and the elimina-

tion of intermediate elements between the diaphragm and opening, I am able to provide the proper balance between the chamber and atmosphere which results in the true rendition of the vibrations of the diaphragm as sound waves and over a greater range of frequency than heretofore possible.

In Figure 4 there is shown a slightly modified form of the invention in which the front board 2a of the box 1a is provided with the opening 3a. In this form the diaphragm 7a projects through the opening 3a a slight distance bringing the attaching rim 11a and fastening lugs 12a outside of the box.

In Figures 6 and 7, a still further modification is shown in which the front board 2b is comprised of preferably porous material such as burlap 13 between the layers of which is loosely provided sound absorbing material 14 of any desired character. The opening 3b is defined by a ring 15 and to which the rim 11b of the diaphragm is secured as by the lugs 12b. In this modification the front edge of the diaphragm 7b is mounted so as to be flush with the front wall of the front board 2b and as in the other cases, the opening 3b in the front board is of a diameter larger than the diameter of the diaphragm 7b and its rim 11b whereby to permit free and direct access to the atmosphere from the chamber 4b.

In Figures 9 and 10 I have shown a further modification in which the box 1c is entirely open at the front as at 3c omitting the front board entirely. In this form there is provided the maximum freedom of passage for the sound waves emanating from the rear of the diaphragm 7c to the atmosphere, it being understood, of course, that the size of the opening 3c is in proper proportion to the size of the diaphragm and the volume of the box chamber as previously explained. In this form, the narrow strip 5c extending from top to bottom of the box supports the loud speaker unit 6c. If desired for decorative purposes, a very thin and extremely porous screen 3d may be provided over the open front 3c but care should be taken to use a material which will not appreciably affect the free and unrestricted passage of the sound waves from the box to the atmosphere.

It is considered a decided advantage to provide this opening or communication between atmosphere and chamber at a point directly adjacent the front peripheral edge of the diaphragm. This is probably due to the fact that the vibration of the diaphragm next to the front edge thereof corresponding to certain low frequencies are very weak and without the direct communication to the atmosphere at this point, coupled with the balancing feature between atmosphere and chamber pressure at this same point, such frequency would be lost to audibility.

With reference to Figures 2 and 8 it will be noted that I have provided an attachment which may be used with facility to increase the amplitude of certain of the sound waves emanating from the back surface of the diaphragm. This attachment comprises the baffles 16 surrounding the diaphragm but spaced apart as shown so as to permit free air communication between the diaphragm and the chamber around the edges of the baffles. These baffles may be held together in this spaced relation by the pins 17 and the entire unit supported in position by the bracket 18.

It will be noted that the baffle unit is positioned short of the front end of the diaphragm. This

is to leave this front portion of the diaphragm, from which the low frequency sound waves largely emanate, uninfluenced by the baffles. The baffles, therefore, act upon the "middle register" 5 frequencies only and tend to amplify them, a desirable function for proper balance of sound translation.

It will be clear too, that the use of this baffle device does not materially affect the free air 10 communication between the diaphragm and the opening 3 to the atmosphere.

Of course, changes may be made in details of construction and arrangement of parts without departing from the spirit and scope of my invention. I do not limit myself, therefore, to the exact form herein described other than by 15 the appended claims.

I claim:

1. A sound apparatus comprising a chamber 20 of determined volume, and a sound unit in said chamber including a vibratile diaphragm, said chamber and both sides of said diaphragm having direct communication with the atmosphere, such communication from the rear side of said 25 diaphragm being through an opening around said diaphragm, said opening being unrestricted in its direct communication with the atmosphere and of a predetermined size to responsively balance the air resistance in said chamber to the vibration of said diaphragm whereby a full range of 30 audible frequencies is reproduced, said opening being of a larger diameter than said diaphragm.

2. A sound apparatus comprising a chamber 35 of determined volume, a sound unit in said chamber including a vibratile diaphragm, said chamber having an opening providing free and unrestricted communication with the atmosphere, said opening being of such predetermined size

and of a diameter greater than said diaphragm so as to responsively balance the air resistance in said chamber to the vibration of said diaphragm whereby a full range of audible frequencies are reproduced, and said diaphragm being so disposed with relation to said opening that there is provided a free and unrestricted passage for the sound waves from all parts of said diaphragm to the atmosphere through said opening. 5

3. A sound apparatus comprising a chamber 10 of determined volume, a sound unit in said chamber including a vibratile diaphragm, said chamber having communication with the atmosphere directly from both surfaces of said diaphragm, and means in said chamber for varying the volume of said chamber. 15

4. A sound apparatus comprising a chamber 20 of determined volume, and a sound unit in said chamber including a vibratile diaphragm, said chamber having communication with the atmosphere 25 directly from both surfaces of said diaphragm, and means in said chamber for varying the volume of said chamber, comprising removable panels slidably mounted therein.

5. A sound apparatus comprising a closed box 25 having a single opening therein providing direct and unrestricted communication to the atmosphere, a loud speaker diaphragm in said box adjacent said opening of less diameter than said opening, the space between said diaphragm and 30 said opening providing a direct and free passage to the atmosphere, and separated baffle members in said box disposed adjacent a portion only of said diaphragm and spaced rearwardly of said opening and the portion of said diaphragm adjacent said opening. 35
